(57) **CLAIM**

The ornamental design for a sports helmet with criss-crossed shaped facemask, as shown and described.

DESCRIPTION

FIG. 1 is a front perspective view of the sports helmet with criss-crossed shaped facemask showing my new design; FIG. 2 is a front view thereof; FIG. 3 is a right side view thereof; FIG. 4 is a left side view thereof; and, FIG. 5 is a top view thereof. The broken lines shown in the drawings represent portions of the sports helmet with criss-crossed shaped facemask that form no part of the claimed design. Broken lines at the ends of solid lines represent the boundary of the claimed design. All surfaces not shown form no part of the claimed design.
